UNITED STATES PATENT OFFICE.

FRITZ ALDENDORFF, OF WILMERSDORF, NEAR BERLIN, GERMANY, ASSIGNOR OF ONE-
FOURTH TO PAUL KOLISCH, OF NEW YORK, N. Y.

ELECTROMECHANICAL DEVICE AND TELEPHONE SYSTEM.

Application filed October 17, 1922, Serial No. 595,187, and in Germany October 19, 1921.

This invention relates in general to telephone systems and more particularly to electromechanical systems in which connections are extended from a preselector or finder trunk to the next trunk ahead through a non-hunting group selector, a finder switch, and an intermediate trunk.

One feature of the invention consists in making the finder switches that extend the connections to the next trunk ahead in the form of quick-acting power driven finders. The power employed may be derived from a motor, gravity or a spring. The wipers of the finders may be caused to fly straight into a group of bank contacts in which a calling trunk is located and then to move step by step until the individual set of bank contacts belonging to the calling trunk is reached. A long, group-marking contact and a short "change-over" contact is coordinated to each group of sets of talking and testing bank contacts. A wiper stopping magnet and a subsequently operating stepping magnet are both energized with the aid of a wiper and the bank contacts of different length brushed over in succession by this wiper. The impelling power spent in setting the quick acting switch is restored when the quick acting switch is released. This restoration is effected by turning the wipers of the switch in the same direction as in setting them onto a calling trunk.

A further feature of the invention, in addition to the several features already mentioned, is that the connections from one switching stage to the next are extended through a two wire trunk and a revertively acting finder whose bank contacts are multiplied with those of other similar finders. A set of relays is permanently associated with each intermediate two wire trunk and means are provided whereby each of a number of practically simultaneous calls will each start only a single different finder, all of which finders may execute their line finding movements simultaneously. The said call receiving relays (line relays) are interdependent in their action.

Another feature of the invention consists in a novel method of grouping the switching apparatus of electromechanical exchanges or of extending existing exchanges. This method enables a board for say, 50 or 100 lines, to be extended to 200 lines without add-

ing special group selectors to the existing equipment. Trunks are run from the connectors of the existing equipment to the pre-selectors of the additional board.

Other features of the invention will appear hereinafter in the description and drawings.

Fig. 1 is a front elevation of the spring impelled switch and

Fig. 2 is a plan view thereof.

Figs. 3, 4 and 5 when placed end to end form a complete diagram of circuits of the novel electromechanical telephone system, Fig. 3 showing calling subscribers' lines and the relays associated therewith, and a quick acting line finder, Fig. 4 showing a first group selector, two wire trunk lines or intermediate trunks extending from the group selectors, and a quick acting intermediate trunk hunting finder; and Fig. 5 showing a final selector or connector consisting of a main voice current switch and two auxiliary switches that steer the wipers of the main switch onto the proper wanted line.

Figs. 6, 7, 8 and 9 illustrate a relay equipped with two armatures, one of which is much more easily attracted than the other, Fig. 6 being a perspective view of the armature end of the relay, Fig. 7 an end view, Fig. 8 a perspective view of a member which serves to hold the armatures in position and to keep them from sticking to each other; and Fig. 9 being a fragmentary vertical section through the more easily attracted armature and its knife edge support or bearing.

Figs. 10, 11 and 12 illustrate a novel method of grouping electromechanical exchanges or of extending existing exchanges without adding group selectors to the existing equipment; Fig. 10 showing a manner of connecting a trunk to auxiliary switches of connectors and running them to the pre-selectors of an extension switchboard; Fig. 11 illustrating a method of running a separate trunk from each connector to the finders of the extension board, and Fig. 12 showing how a two-way trunk may be run from the ordinary contact banks of connectors of one board, or section of a board, to the pre-selectors or finders of another board.

The selector or switch in Figs. 1 and 2 comprises a frame consisting of a top bridge portion 10, two vertical lateral members 11, 11', two inwardly projecting members

12, 12', a rearwardly bent bottom bridge portion or bracket 13, forwardly bent upper bracket 14, and a rearwardly bent upper bracket 15. All the parts 10 to 15 are preferably made of a single piece of sheet iron or metal. Attached by screws 16 to the top bridge 10 of the frame is a bearing bracket 17 (Fig. 2). Supported by a forwardly projecting bracket 18, which forms a part of the lower bridge 13, is a clutch magnet 19 which consists of an iron cylinder closed at the bottom and having a core in its center. The said core is hollow and a screw 20 is screwed into its bottom end. The screw 20 is hollow at its top end and forms the bottom bearing of a shaft 21 which is journaled at the top in the bearing bracket 17. Fixed to the shaft 21 is a ratchet wheel 22 which carries pivots 23 around which an armature 24 is adapted to swing. The one end of the armature (the right hand end in Fig. 1) is normally pressed upward by a spring 25. When the magnet 21 is energized the right hand end 24 of the armature is swung down round its pivot 23 and the left end 26 with its upwardly extending engaging portions is swung upward and caused to effect a coupling between the wheel 22 fixed to the shaft 21 and the wheel 28 fixed to the bushing 29. As will appear from Fig. 2 the wheel 29 has ten perforations 30 into any one of which the upwardly projecting clutching portions 27 can be forced. Fixed to the wheel 28 of the sleeve 29 are two springs 31, 32. In the normal position of the switch the upwardly projecting clutch member 27' forces this spring 31 out of engagement with the spring 32. Also fixed to the wheel 28 are two contact slip rings 33, 34 upon which two contact brushes 35, 36 wipe. The contact brushes 35 and 36 are fixed by screws 37, 38 to a bracket which is attached to the frame of the sleeve releasing magnet 39. The sleeve releasing or starting magnet 39 is fixed by screws 40 to the lateral vertical portion 11' of the frame of the switch and has an armature 41 pivoted at 42 which normally engages with any one of the teeth 43 of the wheel 29 and thus prevents this wheel from rotating. Attached by screws 44 to the left hand vertical portion 11 of the switch frame is a stepping magnet 45 which has an armature 46 pivoted at 47. The armature 46 has an arm 48 whose right hand free end carries a stepping pawl 49 pivotally attached to it at 50. Normally the right hand end of the arm 48 is pulled upward by a spring 51 through a connecting member 52. When the armature 46 is attracted its arm 48 pulls the spring 51 downward and when this spring 51 has executed a certain travel it strikes against an insulating pin 53 and thereby forces a contact spring 54 away from a contact spring 55. The springs 54

and 55 from an interrupter for interrupting the current through the stepping magnet 45.

When the pawl 49 is in its normal position as shown its top oblique end bears against an abutment 56 fixed by screws 57 to the rearwardly extending bracket 15 (Fig. 1). In this position the end of the pawl 49 engages with a tooth of the wheel 22 and prevents this wheel from turning. Backward rotation of the wheel 22 is prevented by a pawl 58.

Firmly attached to the sleeve 29 are insulated brushes or wipers 59. These wipers each consist of two members with split angular ends 60 that bear against each other when they are out of engagement with bank contacts 61, but which press against the two opposite surfaces of a bank contact when in engagement therewith. The wipers always rotate in the same direction, which direction, as viewed in Fig. 2, is clockwise. Fixed to the shaft 21 by a screw 63 is a spring box 64 which contains a clock spring. The one end of this spring is attached to the box 64 and thus fixed relatively to the shaft 21 while the other end of the spring is attached to the bushing 29. In order to prevent the brushes 59 from turning relatively to their bushing or sleeve the external part of the sleeve, which has a round smooth bore, is made square and the holes in the brushes 59 which are threaded over the square sleeve are also made square. Of course a square sleeve of insulation is interposed between the brushes and the middle metal sleeve. The middle ring shaped portions of each brush are held at a certain distance apart by spacing rings 66. Current is conducted to each brush 59 by fixed brushes 67. Each brush 67 consists of two strips of spring metal which are pressed together except at their internal free ends that bear against the inner surfaces of the ring shaped middle portions of a brush or wiper 59.

Normally the top end of the armature 41 engages with a tooth 43 of the wheel 28 which is fixed relatively to the bushing and its brushes 59. The wheel 22 is normally turned into a position in which it is held by the holding pawl 58 and the stepping pawl 49 and in which the clock spring in the spring box 64 has a certain tension which is sufficient, when the armature 41 is attracted, to turn the wheel 28 and the brushes 59 completely around the whole bank of contacts 61 at a comparatively high speed. When the brushes 59 reach a certain group of bank contacts, i. e. a group in which there is a calling line or trunk the magnet 19 is energized as will be more fully explained hereinafter and then the engaging portion 27 of the clutch armature is forced upward. The two members 27 and 27' will at first as a rule enter two adjacent openings 30 of

the wheel 28, but the wheel 28 will continue turning until the radial arm, such as 69, between the two said adjacent openings 30 slips over the spring member 27' and the 5 two members 27 and 27' enter the same opening 30 and thus rigidly couple the wheels 28 and 22 together. The spring in the spring box is then prevented from turning the sleeve 29 with the brushes 59 further 10 relatively to the shaft 21 and the whole rotor consisting of the bushing 29, the brushes and the shaft 21 is brought to a dead stop, because the free end of the pawl 49 engages with a tooth in the wheel 22 and thus prevents 15 the rotary impulse, imparted to the rotor by the swinging round of the brushes 59, from carrying the wheel 22 round after the two wheels 22 and 28 have been coupled by the members 27 and 27'. When the 20 brushes 59 have thus been stopped, circuits are closed which have the effect of sending stepping impulses through the magnet 45. The brushes 59 which had been whirled round in a continuous movement by the 25 spring in the spring box are now stepped forward by the stepping magnet 45 until the particular calling line or the bank contact thereof is reached. Other circuit changes are now effected by which the releasing magnet 39 is deenergized again and at the same time, or at a later period, stepping impulses are again sent through the magnet 45, the magnet 21 being deenergized 30 at this time so that the wheel 29 is turned clockwise until one of its teeth engages with the free end of the armature 41 and the stepping pawl 49 turns the wheel 22 in a clockwise direction relatively to the wheel 29 until the clutch member 27' strikes 35 against the insulating boss 70 of the spring 31 so as to separate it from the spring 32 and thus open the circuit of the stepping magnet 45. The spring in the spring box 40 64 will now be rewound and the wipers 59, which will now be standing near the beginning 45 of a group of bank contacts, will be ready to be whirled around again for the purpose of effecting another connection. The circuits involved in the performance of 50 the above described results will be explained in the description of Figs. 3 and 4.

The contact bank 71 has three rows of 55 bank contacts 72 each and a fourth row of bank contacts 73. For every ten bank contacts 72 there are two bank contacts 73 one of which covers practically the same arc of a circle as is covered by nine bank contacts 72 and the arc of the second contact 73 corresponding to that of one contact 72. 60 Hence two contacts 73 occupy an arc which corresponds to that of ten contacts 72. The bank contacts are held between two arcuate metal members 75 and 76 and three spacing arcuate members 77, 78, 79. The bank contacts are embedded between arcuate strips of 65

insulation. One of the arcuate spacing members as 77, has two downwardly bent lateral members or parts 80, 81 with upwardly projecting ears 82, 83 by means of which the switch is fixed to the pillars or 70 uprights 84, 85 of a switch rack. The frame 10, 11 of the switch is fixed by hollow screws 86, 87 to the downwardly bent parts 80, 81 of the contact bank. The hollow screws 86, 87 are fixed to the members 80, 81 by means 75 of screws 88, 89. By turning the screws 86, 87 the center of the shaft 21 can be shifted relatively to the contact bank and this permits of a proper adjustment.

Instead of building up the contact bank 80 in the manner described the bank contacts may be held in their proper positions relatively to each other in a mould and an insulating substance which has a relatively high melting point may be liquefied in the 85 mould or squirted in in a molten state and then be allowed to cool in the mould. The bank contacts will then be firmly held in the insulating material, such aslonarith, when the latter has cooled down and become hard. 90 Contact banks can be built in this way at a low cost. This method of constructing contact banks is explained at length hereinafter.

Referring now to Fig. 3 100 represents a switch of the kind described above. It has 95 three arcuate rows of bank contacts 72^a, 72^b, 72^c, which correspond to the bank contacts 72 shown in Figs. 1 and 2 and one row of contacts 73^a, 73^b corresponding to the contacts 73 shown in Fig. 1. The arc occupied 100 by a group of ten contacts 72^a corresponds to that occupied by one long contact 73^a and a short companion contact 73^b. In Fig. 3 each subgroup of contacts 72 is illustrated as consisting of three contacts, whereas in reality there are preferably ten contacts 72 in a subgroup. The rows of contacts 72^a, 72^b, 72^c and 73 are wiped over by brushes 59^a, 59^b, 59^c and 59^d respectively. The magnets 39, 19 and 45 shown in Fig. 3 correspond to those similarly designated in Figs. 1 and 2.

The circuits and general operation of the system will be understood from the following description of the operations involved in the establishing of a connection between two subscribers.

When the subscriber 101 raises his receiver, his line relay 102 and a finder starting relay 103 which is common to a group 120 of subscribers, receives current that flows from the negative pole through 103, armature contact 104 of a line relay belonging to the subscriber's line 101', contact 105 of the line relay 102 of the calling subscriber 101, 125 through contacts 105 on the line relays of the other subscribers of the group, wire 106, armature contact 107, left hand winding of line relay 102, armature contact 108 of the cut-off relay 109, line wire 110, subscriber's 130

station 101, line wire 111, armature contact 112 to the positive pole. In this circuit the relay 103 which has a high and a low resistance winding energizes first, and when its armature closes the contact 113 so as to short circuit its high resistance winding the relay 102 receives sufficient current to close its contact 114 and open its contact 105, the contacts 105 and 114 being controlled by an easily moved light armature such as 5 in Fig. 6 and the other contacts of the relay 102 being controlled by a second armature such as 3 of Fig. 6 to operate which a strong magnetization of the relay is necessary. By the energization of the relay 103 which is slow to release its armature, a finder starting contact 115 and a contact-group designating contact 116 are closed. The contact 115 closes a circuit for the finder starting magnet 39, this circuit extending from the negative pole through 115, 117, contact 118 of a relay 119, starting or releasing magnet 39, resistance 120 to the positive pole.

When the armature 114 of the line relay 102 is closed a current flows from the positive pole through a resistance 121, contact 122, 114, right hand winding of the line relay 102, and this winding serves to keep the light armature of the line relay 102 attracted. If another subscriber calls at this moment his line relay, say 102, will not be energized because the lead 106 through which current is supplied to all the line relays is disconnected from the starting relay 103 and therefore also from the negative pole of the battery at the open contact 105 of the line relay 102. Hence for a brief interval other subscribers are prevented from sending a line finder starting impulse over the starting wire 107.

When the finder starting magnet 39 is energized over the starting wire it closes a locking circuit for itself at its contact 123 and an energizing circuit for a relay 119 at its contact 124. It also closes a contact 125 whereby a strong current impulse is sent from the positive pole over the wire 126, contact 122, 114, right hand winding of the line relay 102 to the negative pole. This strong current impulse magnetizes the line relay 102 sufficiently to cause it to operate its armature springs 127, 128, 129, 130, 131. The line relay, whose contact 122 is now open, is kept energized by a holding current which flows from the negative pole through the right hand winding, contacts 114, 132, 129, left hand winding of the line relay 108, 110, 101, 111, 112 to the positive pole. The wire 106 is now reconnected through 128 to the common relay 103 and therefore to the negative pole of the battery so that another subscriber will now be able to send a starting current impulse through the starting wire 117, contact 135, wire 136 to the next finder.

It will be obvious that the partial energization of the line relay 102 and the ensuing full energization of the same through the closure of the contact 125 will take place in a fraction of a second so that a second calling subscriber may send in his call practically simultaneously, and even if he calls at exactly the same instant the two calls will be dealt with one after the other, that is to say one call will effect the starting of one finder and a fraction of a second later the other call will effect the starting of another finder.

The moment a subscriber calls, the subgroup marking contact 116 of the starting relay 103 common to the subgroup of say 10 subscribers to which the calling subscriber belongs, connects the negative pole to the subgroup designating wire 137 and to the subgroup marking contact 138. Immediately afterwards this designating potential is applied to the contact 138 through the contact 131 of the calling subscriber's line relay 102. It will be understood that the subscribers' line relays 102 are grouped in subgroups for say 10 subscribers and that all the contacts 131 of the relays of a subgroup are connected to one subgroup designating wire 137 which is connected to one subgroup marking bank contact 138.

The finder 100, being started by its starting magnet 39 as described, its wipers 59^a, 59^b, 59^c, 59^d are whirled round by spring power and when the wiper 59^d reaches the long subgroup designating contact 38 the wiper stopping magnet or clutch magnet 19 is energized by a current which flows from the positive pole through 19, contact 139 of relay 140, wiper 59^d, long contact 138, wire 137 and then either to contact 116 or contact 131, or through both of these contacts to the negative pole. On account of the length of the contact 138 the clutch magnet 19 has sufficient time to energize so as to couple the wipers 59^a, 59^b, 59^c, 59^d with the finder shaft. When this coupling operation is completed the wipers will have reached the short contact 142 which is located at the beginning of the subgroup of bank contacts to which the calling subscriber is connected. It will thus be noted that the subgroup designating bank contacts are displaced in the contact bank with respect to the line contacts 72^a, 72^b, 72^c in such a manner that the wipers are enabled to stop at the beginning of the subgroup of line contacts in which the calling line is situated. When the wiper 59^d makes a pause on a contact 142 the relay 140 is given time to energize in a circuit which extends from the positive pole through 19, 139, 59^d, 142, wire 143, armature contact 144, relay 140, off normal contacts 30, 31 which will be closed at this time to the negative pole. The relay 140

on energizing cuts the magnet 19 into its circuit which extends from the positive pole through the contact 145, winding 140, 30, 31 to the negative pole. The energization 5 of the relay 140 results in the stepping magnet 45 being energized by a current which flows from the negative pole through armature contact 146, 45, interrupter 54, 55, contact 147 to the positive pole. The stepping 10 magnet 45 now steps the wipers of the finder round until the contact 148 is reached which is connected through wire 149, contact spring 127 of the line relay 102 to the cut-off relay 109 and to the positive pole. When 15 the contact 148 is reached by the brush 59^a the test relay 150 is energized by a current which flows from the negative pole through 31, 30, 151, 150, 59^a, 148, 149, 127, 109 to the positive pole. The relay 150 opens the 20 circuit of the stepping magnet 45 at the contact 147 and the cut-off relay 109 disconnects the line relay 102 and the positive pole of the battery at its contacts 108 and 112 respectively, while connecting the wire 25 149 to the cut-off relay through the armature spring 152. The relays 150 and 109 are now kept energized through the armature spring 152. The relay 150, by short 30 circuiting a part of its winding, places a busy potential on the test wire 149 and on the test wire 160 leading to the bank contacts of the connectors. The calling subscriber 101 is now connected through the wipers of the finder 100 and through the 35 contacts 170, 171 of the test relay 150 to the impulse relay 201 belonging to the group selector, the relay 201 being energized by a current that flows from the negative pole of the battery through the left hand winding 40 of relay 201, 170, 59^a, bank contact, wire 172, 173, 174, 110, calling subscriber 101, 111, 175, 176, 177, bank contact, wiper 59^b, 171, contact 202 of relay 203 to the positive pole. 45

It is to be noted here that when the relay 140 of the line finder was energized, the relay 119, which was previously energized through contact 124, receives current through contact 155 by which it is kept 50 energized until the line finder is restored as described hereinafter. The relay 119 at its contact 156, short circuits the starting magnet 39 so that this magnet allows its armature (41, Fig. 2) to drop back. In this 55 position this armature 41 is in readiness to engage with a tooth as 43 of the wheel 25, Fig. 1, when the finder is restored in the manner hereinafter described.

The calling subscriber who has now been 60 connected through to the first group selector 200 as described sends in the dialling impulses by which the group selector is caused to place its wipers 204, 205 onto the bank contacts of a trunk, as 212, 213, that leads 65 to a group of finders 300 allocated to the

group of switches to which the wanted subscriber is connected. Before the said dialling impulses are sent in, the release relay 214 is energized by a current which flows through the contact 207 of the energized relay 201, 214, resistance 216 to the positive pole. The relay 214 closes a locking circuit for itself through the contact 218 which remains closed until the calling subscriber hangs up his receiver. The dialling group 70 selecting impulses sent in by the calling subscriber result in impulses flowing from the negative pole to 218, back contact 210 which is closed each time the line relay is deenergized, contact 219 which is kept closed 75 by the changeover relay 215 whilst the dialling impulses are being sent in, wire 220, stepping magnet 206 to the positive pole of the battery. When the wipers 204, 205 have thus been stepped onto the wanted trunk the 80 line relay 201 keeps its armatures continuously attracted for a relatively long interval and the change over relay 215 is then short circuited by the contact 209 long 85 enough to cause its armatures to fall back 90 so as to close the contacts 221, 222, 223. A current then flows from the positive pole through 221, 211, contact 226 of relay 203, wiper 204, wire 212, contact 227 of the cut-off relay 228, left hand winding of the relay 229, contact 230, lead 231, contact 232 and the contacts 233 of the other relays such as 229' belonging to the subgroup of trunks that are connected to a subgroup of bank 95 contacts of the trunk finders 300, starting 100 relay 240 to the negative pole of the battery. The starting relay 234 sends a starting impulse to the starting magnet 39' of the finder 300 through the starting wire 237 and the moment the finder 300 is started it sends 105 an impulse back through the contact 239 and the wire 240 which causes the relay 229 to attract its heavy armatures and to thus disconnect itself from the lead 231 which is 110 common to all the relays of the entire group of trunks connected to all the bank contacts of the finder 300. Before an impulse was sent back from the line finder 300 over the lead 240 as described the relay 229 after its initial energization, was kept energized by 115 a current from the positive pole through 242, 243, 241, right hand winding of the relay 229 to the negative pole similarly as in the case of the line relay 102, Fig. 3.

The starting relay 234 and the relay 229 120 connect the negative pole of the battery through their contacts 236 and 244 respectively to the subgroup designating wire 245 and to the subgroup designating contact 246 belonging to the particular subgroup of intermediate trunks in question. The finder 300 whirls its wipers 59^a, 59^b, 59^c, 59^d round and these wipers are stopped at the beginning of the subgroup of bank contacts in which the calling trunk is located. Then 130

the wipers are stepped onto the calling trunk and this trunk 212, 213 is extended through the contacts 270, 280 of the relay 250 to the trunk 301, 302 connected to the final selector 400. The operations of the trunk finder 300 being similar to those of the line finder 100 it is deemed unnecessary to describe them in further detail.

When the trunk 212, 213 is connected through the finder 300 to the trunk 301, 302 the line relay 303 of the connector or final selector is energized by a current which flows from the negative pole through 303, 270, 59°, bank contact, wire 281, trunk wire 212, wiper 204, contact 226, 219, 221 to the positive pole. The relay 303 on energizing closes its contacts 316, 317 and the release relay 314 is energized by a current from the negative pole through 316, 314, resistance 318 to the positive pole. The release relay closes a locking circuit for itself at the contact 320 and at the contact 321 it connects the negative pole to the relay 250, whilst at its contact 321 it closes an energizing circuit for the relay 323, this relay completing a locking circuit for itself which extends through armature contact 324 and through the off normal contact 325 of the finder 300. The relay 323 opens its contact 326 and thus prepares the restoring operation of the trunk finder 300 which will be more fully described later.

At this juncture it must be mentioned that when the group selector 200 left its normal position its off normal contacts 224, 225 were closed, the contact 224 preparing a restoring circuit for the group selector and the contact 225 short circuiting the change-over relay 215. The change-over relay is deenergized after the first set of dialling impulses has been sent in and the group selector wipers have been set onto the proper trunk. By this means the change-over relay 215 is prevented from being energized again (via 218, 215, 217, positive pole) when its short circuiting contact 209 is opened during the sending in of the succeeding series of dialling impulses by which the final selector is caused to move its wipers onto the wanted line. Hence when the second series of dialling impulses is sent in and the contact 211 is opened a corresponding number of times, the line relay 303 at the final selector will allow its armature to drop back at each opening of the contact 211 and a corresponding number of impulses will flow from the negative pole of the battery through 320, 327, 328 of the change-over relay which is energized during the dialling impulses, by a current that flows through contact 329 of relay 330, stepping magnet 352 of the tens group designating switch T_d to the positive pole. The tens designating switch T_d marks the particular group of bank contacts onto which the wipers 353,

354, 355, 356, 357 of the voice current switch or main switch of the connector 400 is to be set. This marking of the proper bank contact group is effected by means of the arcuate member 358 with its associated bank contacts 359, 360, 361 and the group designating contacts 362, 363, 364. It will be supposed that the wanted subscriber is in a second group of bank contacts, i. e. in the group corresponding to the long contact 363. This being the case, two impulses will be sent through the stepping magnet 352, and the arcuate member 358 will be stepped round so as to connect the negative pole with the two contacts 359, 360. A circuit is then closed which extends first from the negative pole through 358 and 359 to the brush 357 and then through the contacts 360, 362 when the brush 357 has been stepped from the contact 370 onto the contact 362. This circuit through the brush 357 extends further through the wire 371 and the relay 372 to the positive pole, the relay 372 closing the circuit of the operating magnet 374, and this circuit extending from the positive pole through the interrupter 375, operating magnet 374, contact 376 of relay 377, contact 373 to the negative pole. The brushes 353, 354, 355, 356, 357 are now driven forward by the operating magnet 374 until the brush 357 has passed over all the designating contacts that are connected by the arcuate member 358 to the negative pole, these designating contacts being, in the case under consideration, only the contact 362, so that when the brush 357 leaves the long contact 362 the relay 372 will be deenergized to open its contact 373 and switch off the operating magnet 374. While the wipers 353 to 357 are thus being driven forward into the proper subgroup of bank contacts the subscriber may be sending in the last series of dialling impulses. During the pause which ensued before the final series of impulses were sent in, the change-over relay 315 was short circuited at the contact 317 so that it closed its contact 332 to energize the relay 330 by a current which flows from the positive pole through 332, upper winding of relay 330, contact 359, arcuate member 358 to the negative pole. The relay 330 closes a locking circuit for itself which extends from the positive pole through 331, 380, 320 to the negative pole. Hence the last series of dialling impulses results in stepping impulses flowing from the negative pole through 320, 327, 328, 350, through the stepping magnet 381 of the units designating switch U_d to the positive pole. If the last series of dialling impulses comprises three impulses the wiper 382 will be stepped onto the third units designating contact 383, the other wipers 384, 385, being stepped onto curved contact strips 386 and 387 respectively. When the relay 372,

which was energized by current through the long group designating contacts, is deenergized, a circuit is closed for the operating magnet 374 which extends from the negative 5 pole through the curved contact 378 of the units designating switch, wiper 385, contact 388, 376, 374, interrupter 375, to the positive pole. The operating magnet 374 now drives the wipers of the main switch 10 forward until the wiper 356 strikes a bank contact connected to the bank contact 383 onto which the wiper 382 of the units designating switch is stepped. When the wiper 356 reaches the said bank contact the circuit of the operating magnet 374 is opened 15 at 376 on account of a current flowing from the positive pole through 332, 390, 391, 382, 383, 392, 356, relay 377 to the negative pole. The relay 377 closes a test circuit at its contact 393 and a test current then flows 20 through 394, test relay 395, test wiper 355, test wire 160, contact of the wanted subscriber's line relay, cut off relay of the wanted subscriber corresponding to 109, 25 positive pole. If the wanted subscriber is free, the test relay 395 will be energized and will close its contacts 396, 397, 398, 399, 400, 401. By closing its contact 396 the test relay 395 establishes the busy condition on the test 30 wire 160 so as to prevent other connectors from connecting to the same wanted line. At its contact 399 the test relay establishes a circuit for the ringing relay 347, this circuit extending from the negative pole 35 through the curved contact 378, wiper 385, 399, upper winding of relay 347 to the positive pole. Ringing current from the ringing generator 346 is thus applied through the contacts 349, 345 and 400, 401 to the 40 wanted line immediately the test relay responds. When the test relay 395 responds it also immediately connects the interrupter 403 to the stepping magnet 381, via 397, 404, 405, 384, 386 and the units designating 45 switch is sent by these impulses back into its normal position, the circuit through the operating magnet 381 being opened when the wiper 384 and its companion wipers 382, 385 reach their normal position. When the 50 circuit of the ringing relay 347, which extends through 387, 385, 399 is opened by the wiper 385 regaining its normal position the ringing relay 347 is closed periodically by the interrupter 411 which sends current impulses through 398, 340 and the lower winding of the ringing relay 347.

When the called subscriber responds a current flows through the ringing cut off relay 342, this relay then opening the circuit of the ringing relay at 343 and closing the circuit of an auxiliary release and metering relay 336 at its contact 341. The relay 336 closes a locking circuit for itself which extends from the positive pole through the left hand winding, contact 388, 320 to the nega-

tive pole. At its contact 337 the metering relay closes a circuit which extends from the positive pole through the retardation coil 415, 387, 280, 59^c, 295, 213, 205, 223, 296, relay 203 to the negative pole. The relay 203 closes its contacts 297, 298, 299, 299^c, 298^c and thus connects the translator 297 in the trunk line. The relay 203, which closes a locking circuit for itself that extends through 299^c, 296^c, 295^c to the positive pole, may also close a meter circuit which is not shown in the drawing, but which may extend either through the test wire and test wiper 59^c to a meter that is connected in parallel to the cut off relay 109 of the calling subscriber, or through a separate metering circuit which extends through a separate wiper on the finder 100.

The subscribers can now converse through the repeating coil 297^c, the calling subscriber receiving his microphone feed current through the two windings of the line relay 201 and the contact 299 of the relay 203, while the called subscriber receives his microphone feed current through the windings of the relay 342 in the connector.

Assuming that the calling subscriber replaces his receiver first, the line relay 201 will be deenergized and will short circuit the release relay 214 on contact 208. When the armature of the release relay 214 drops back a restoring circuit is closed through the interrupter 292^c, contact 293^c, 224, 220, operating magnet 206 to the positive pole. The operating magnet 206 then rotates the 100 wipers 204, 205 until they reach their normal position, when the off normal contacts 224, 225 are opened and the interrupter 292^c is switched off.

The deenergization of the release relay 105 314 also results in the circuit of a test relay 150 being opened at 280^c so that the relay 250 allows its armatures to drop back and the stepping magnet 45 of the line finder is energized by current impulses which flow 110 from the positive pole through 147, individual interrupter 55, 54, contact 146 to the negative pole. The stepping magnet now steps the wheel 22, Fig. 1, round and thereby turns the shaft 21 which, it will be remembered, is mechanically connected through the spring in the spring box 64, Fig. 1, to the sleeve 29 that carries the brushes. The sleeve and the brushes 59 are at first rotated with the shaft until the wheel 120 28 is turned into a position in which the tooth, as 43, nearest to the armature 41, Fig. 1, strikes against this armature. The wheel 28 will then be prevented from turning further and then the ratchet wheel 22 of the finder will be turned alone so as to retension the spring in the spring box 64. When the spring has been fully retensioned the member 27, Fig. 2, will strike against the button 70 and will open the off normal 130

contacts 31, 32, see Figs. 2 and 4. When the off normal contacts 30, 31, Fig. 3, are opened the relay 140 and the magnet 19 are deenergized and the circuit of the relay 119 is also opened at the contact 155. The line finder 100 and the group selector 200 will now have been restored to their normal positions. When the relays 201, 203 were deenergized as described by the calling subscriber replacing his receiver, the relay 303 in the connector was also deenergized and at its contact 450 it short circuited the release relay 314. When the relay 314 allows its armatures to drop it opens the circuit of the 15 finder test relay 250 at the contact 321 and thus causes the finder 300 to be restored in the same way as the finder 100. By opening the contact 334 the release relay 314 opens the locking circuit of the relay 377 and at its contacts 320 it opens the locking circuit of the relay 336 so that this relay is deenergized when the relay 342 is deenergized through the called subscriber replacing his receiver. The release relay 20 314 also connects the interrupter 450 through its contact 335 to the curved bank contact 451 of the tens designating switch, and the operating magnet 352 of this switch then steps its wipers round until the wiper 452 lands upon the contact 453. When the wipers of the tens designating switch T_d are thus stepped round, the arcuate wiper 358 connects the negative pole to all of the long contacts 362, 363, 364 and this results in the 25 relay 372 being energized by a current from the negative pole through the arcuate wiper 358, long contacts, wiper 357 of the main switch, relay 372 to the positive pole. The operating magnet 374 of the main switch 30 then receives current through the contact 373 of the relay 372 and drives the wipers round until they are restored to their normal position in which the wiper 357 rests upon the normal contact 370. The arcuate 35 wiper 358 will now be standing on all the contacts of its bank except the contact 359. The relay 372 is therefore deenergized when the wiper 357 reaches the contact 370 and an impulse is then sent from the interrupter 460 through the contact 461, 453, through 452 and the operating magnet 352 to the positive pole. This impulse restores the arcuate wiper 358 to its normal position in which it stands adjacent to the contact 359 without contacting therewith.

The marginal line relays 102, Fig. 3, and 229, Fig. 4, are constructed as shown in Figs. 6 to 9. The relay has a light, easily moved armature 5 and a heavy armature 3 both mounted on a knife edge at one end of its iron limb 2. The light armature 5 is located in the densest part of the magnetic field produced by the iron core of the relay winding 1, while the heavier armature 3 is 60 acted upon by a magnetic field which is not

nearly as dense as that which acts upon the armature 5. By this means the armature 5 is made to respond much more readily than the heavier armature 3. To prevent the easily moved armature 5 from sticking to the armature 3 a spacing member is employed which is shown in perspective view in Fig. 8. The two lugs or ears 6 maintain proper gaps between the sides of the armature 5 and the two vertical side members of the armature 3. The spacing member is fastened to the light armature by screw 8. The point 9 of this screw enters a cavity in the end of the limb 2 as shown in Fig. 9. The overhanging portions 7 attached to the spacing member serve to hold the armature 3 in its proper position on the knife edge as illustrated in Fig. 7.

It will be obvious that several line finders of the kind described above may be interposed in tandem between the calling lines and the numerical switches.

Figs. 10 to 12 which illustrate circuit arrangements for effecting trunk connections between two different exchanges or groups will now be described.

In an exchange equipped with connectors or final selectors whose wipers are set onto the wanted line by means of designating switches (group designating switches and line designating switches) connections intended for another exchange may be established over inter-exchange or trunk lines by means of the designating switches. The inter-exchange trunks may lead from the bank contacts of the designating switches of the one exchange to the preselectors or line finders of the second exchanges. This arrangement also constitutes a convenient method of extending existing exchanges. If for example an establishment is provided with an automatic board whose ultimate capacity is 50 or 100 lines and it is desired at a later period to install another 50 or 100 lines a second board may be put in, and one or more trunk lines may be run between the two boards which will give inter-group or inter-exchange connecting facilities. Instead of establishing the connections with the other exchange through the banks of the designating switches the trunk connections may be established through the main wipers of the final selectors.

Fig. 11 shows an arrangement in which a single trunk 476, 477 is run from the tens designating switch T_d to the preselectors or line finders of another board which is assumed to be of the type shown in Figs. 3 to 5.

In the circuit arrangement illustrated in Fig. 11 a separate trunk 477', 478' is run from each tens designating switch T_d in the switch group to the other board. The trunks 477, 478 of Fig. 10 and 477', 478', Fig. 11, are wired at the second board ex-

actly like the ordinary subscribers' lines shown in Fig. 3.

It will be assumed that a calling subscriber has been connected through to a connector of the kind shown in Fig. 10 and that this subscriber desires a connection with a line connected to another board. When the subscriber is connected through to the trunk 301, 302 the line relay 303 is energized in the manner explained in connection with Fig. 5 and the release relay 314 is then also energized, while the changeover relay 315 is prevented from being energized by a short-circuit that is closed at 317.

To obtain a connection with the other board the calling subscriber sends in one dialling impulse and this results in one operating impulse flowing through the operating magnet 352 over the following path: negative battery pole, 320, 327, 328, 329, 352, positive battery pole. The wipers 452, 358, 470, 471, 472 of the tens designating switch T_d are thus rotated one step and the wipers 470, 471, 472 land on the bank contacts 473, 474 and 475 respectively, while the wiper 358 remains in contact with bank contact 490, because it takes two steps to shift it off 490 and onto the bank contact 359. The wiper 452 does not reach the arcuate bank contact 451 until it is rotated two steps.

When the said selecting or dialling impulse has been sent in, a pause ensues during which the change-over relay 315 (which is energized by current from the negative pole, through 320, 315, 319 to the positive pole) is deenergized by the short circuit closed at 317, and a test circuit is then closed as follows: negative pole, 480, wiper 358, 490, 491, test relay 479, test bank contact 473, test wire 492, resistance 493, positive pole. If the trunk 476, 477 is engaged by a connection established through some other tens designating switch T_d , the potential on the test wire 492 will be too low to energize the test relay 479, and the calling subscriber will receive a busy signal (by any preferred means not shown), but if the trunk is free the test relay 479 will be energized and it will close its contacts 482, 483, 493' while opening its contact 480. By the direct application of the negative pole to the contact 493' the positive potential on the test wire 492 is lowered to such an extent that the test relays of other tens designating switches whose wipers are subsequently set onto the trunk 476, 477 will not be energized sufficiently to attract their structures.

When the contacts 482, 483 of the test relay 479 are closed as described a current flows from the positive pole through the retardation coil 484, contact 485 of relay 303, 348, 482, 472, 475, trunk wire 476 and then through the line relay of the trunk at the second board, which trunk and line relay are wired like the subscribers' lines shown in

Fig. 3. The line relay at the second board now responds and this results in the connection being extended to a group selector or to a final selector like that shown in Fig. 10. Assuming that the calling subscriber has now been connected through a final selector, he will send in two more series of dialing impulses, the first series operating to set a tens designating switch which may be like the one shown in Fig. 10, or like that shown in Fig. 5. The final series of dialling impulses operates to set a units designating switch such as U_d at the final selector of the second board and the wipers of the final selector will then be steered onto the bank contacts of the wanted line. When the wanted subscriber responds a relay at the final selector is energized which causes a current to flow back over the other wire 477 of the trunk and through 474, 471, 483, 496, 344, relay 342 to the negative pole. The relay 342 is thus energized and sends an energizing current through its contact 341 to relay 336 while connecting the talking circuit through at its contact 485. The relay 336 sends an impulse back towards the calling subscriber through closing its contact 337. This impulse affects the repeater at the previous selector or selectors and may serve to operate a subscriber's meter or the like.

It will be noted that the brushes 353, 354, 355, 356, 357 of the final selector, Fig. 10, have not been affected in any way in establishing a conversational connection through the tens designating switch T_d that belongs to the final selector in the first board.

If the called subscriber hangs up first at the end of the conversation the deenergization of the relay 342 results in the negative pole being applied continuously through 340, 339 to the right hand end of the release relay winding, so that the release relay 314 will be short-circuited and caused to close a restoring circuit at its contact 335 which extends from the negative pole through the interrupter 450, 335, 497, arcuate bank contact 451, wiper 452 of the tens designating switch, magnet 352, to the positive pole. The magnet 352 now drives the wipers 452, 358, 470, 471, 472 forward until the wiper 452 reaches the bank contact 453. A final restoring impulse then flows from the negative pole through 460, 461, 453, 452, 352 to the positive pole and this rotates the wipers into their normal position. While the wipers of the designating switch are thus rotated forward until they reach their normal position the relay 479 is kept energized by a current from the negative pole through 493', 479, 470, arcuate contact 497 to the positive pole and the negative pole is thus kept disconnected at 480 from the arcuate wiper 358 so as to prevent the brushes 353—357 of the main switch of the final selector from being moved by currents sent through the contacts

359, 360, etc. to the operating magnet 374 and to the relay 372 which would switch on the magnet 374 through its contact 373.

The restoration of the other switches such as the preselectors, group selectors, etc. involved in the talking connection, is effected in the manner hereinbefore described.

In cases in which a calling subscriber who has been connected through to the trunk 301, 10 302, wishes to connect to another subscriber belonging to the same board, i. e. to another subscriber connected to the contact bank brushed over by the wipers 353, 354, 355, 356, 357, Fig. 10, he will send in two or 15 more dialling impulses to operate the tens designating switch T_d and this will result in the wipers 452, 358, 470, 471, 472 being stepped round two or more, say three, steps. The arcuate wiper 358 will then leave the contact 20 490 and establish connection with the bank contacts 359, 360 before the contact 491 is closed during the pause between the penultimate and the last series of dialling impulses. Hence, no test current will flow through 480, 25 358, 490, 491 and through the test relay 479, so that the talking current wipers 472, 471 of the designating switch will remain dead in any case. On the other hand negative battery will be applied from 480, 30 through 358 to the bank contacts touched by the arcuate wiper 358 and the operating magnet 374 of the wipers 353, 357 will rotate these wipers and cause them to be set onto the wanted line in the manner hereinbefore described. When the wanted subscriber responds the relay 342 will be energized and will cut off the ringing relay 347 and connect the calling subscriber through to the wanted line. The restoration of the 35 40 designating switches T_d , U_d and of the main switch wipers 353—357 is also effected in the manner hereinbefore described.

Only slight changes of the circuits of Fig. 10 are required to adapt them for trunking 45 to another board by means of several trunks, instead of by one outgoing trunk only. These changes are indicated in Fig. 11 which represents the right part of Fig. 10 with the required alterations, the left part being 50 omitted as it would be precisely similar to the corresponding left part of Fig. 10. An inspection of Fig. 11 will show that the said alteration consists 1 in omitting the test wire 492 of Fig. 10 with the associated resistance 493, 2 in providing a single arcuate bank contact 497' instead of two contacts 497 and 473, Fig. 10, and 3 in running a separate trunk 476', 477' from each tens designating switch, instead of having a single 55 trunk 476, 477 multiplied over all of the tens designating switches T_d of the selector group.

When the wipers 472', 471', 470' are rotated one step by a single dialling impulse 60 65 that affects the magnet 352 the relay 479,

which does not act as a test relay in this case, is energized and connects the calling subscriber through the trunk 476', 477' which is connected at the line finders of the second board like an ordinary subscriber's line. 70 The trunk 476', 477' is then connected by an idle line finder to a numerical switch through which the conversational circuit is established in the manner described in connection with Figs. 3, 4 and 5. 75

The restoration of the switches after the conversation is also effected as already explained in connection with Fig. 10.

From the foregoing description it will be apparent that in an arrangement according 80 to Fig. 10 the inter-exchange or inter-board trunk 476, 477 is multiplied over the tens designating switches and also over the line finders at the second board, while in an arrangement according to Fig. 11 the interboard 85 trunks each emanate separately from a designating switch T_d and are multiplied over the line finders at the second board only.

Fig. 12 shows the circuits of a final selector according to Fig. 5 modified for inter-group or inter-exchange trunk working, only such of the circuits being shown as are deemed necessary for a clear understanding of the inter-exchange trunking operations. The final selector corresponds in all details 95 to that hereinbefore described except that a wiper 500, a relay contact 501, a relay contact 500, and a row of bank contacts amongst which are 502, 503, 504 are added. Such of the parts of the final selector as are deemed necessary to enable the operation to be understood have signs of reference that correspond to those used in the figures hereinbefore described except that an index "2" 100 is added to them.

It is assumed that the first three lines 505, 506—507, 508—509, 510 leading from the contact bank of the selector are trunks leading to another exchange or board. At the second board 600 these trunks are multiplied 110 over the bank contacts of line finders similar to those hereinbefore described. Also connected to the bank contacts of these finders (not shown) are ordinary subscribers' lines, as line 110³, 111³. 115

The arrangement of the connector or final selector 400' in the first board is such that when its wipers 353², 354², 355², 500, 356², 357² are set onto a trunk, as 505, 506 leading to the second board, these wipers will move from one trunk to another until a free trunk is found. For each such group of inter-board or inter-exchange trunks there is a set of bank contacts 502, 503, 504 all of which are connected to the negative pole of the battery as shown, except the last contact 504 of the set, which is dead. These contacts with their cooperating wiper 500 form a part of the means by which the wipers of the connector 500' are caused to rotate until an idle 120 125 130

one of a set of equivalent trunks 505, 506—507, 508—509, 510 is found.

The wiring and equipment of the inter-board trunks differs slightly at the second board 600 from that of the subscribers' lines 110³, 111³, the trunks being each provided with an alternating current relay 527, a condenser 551, and a resistance 528 in addition to a cut-off relay 517 and a two-armature relay 530, while the subscriber's lines 110³, 111³ have only a cut-off relay 109³ and a two-armature relay 102³ like the ordinary subscribers' lines connected to the line finders of Fig. 3.

15 A common line-finder starting relay 103³ corresponding to relay 103 hereinbefore described is provided for all the lines (trunk and subscribers') connected to the banks of the line finders of the board 600. A condenser 552 is connected in parallel to the relay 103³ so as to provide a by-path of low resistance for the alternating currents by which the alternating current line relays 527 of the inter-board trunks are energized.

25 The line finder starting wire 117³ and the "return-impulse-wire" 126³ at the board 600 correspond to similar wires 117 and 126 of Fig. 3 hereinbefore described. The branch wires 172³, 177³ are connected to a set of bank contacts of the line finders (not shown) at the second board 600.

The inter-board trunks 505, 506—507, 508—509, 510 are two-way trunks and are connected at both boards to the bank contacts of final selectors, as 400', and of line finders, the wires 511, 512, 513 being the normals that are multiplied over the banks of the line finders of the first board, and the wires 514, 515, 516 being the normals that are multiplied over the banks of the final selectors of the second board. Hence, when a call proceeds from the first board, a line relay, as 527, of the second board will be energized over a trunk, as 505, 506, which will result in a line finder of the second board seizing the trunk, and when a call proceeds from the second board 600 a line relay similar to 527 at the first board will be energized and this will result in a line finder (not shown) of the first board, similar to the finders of Fig. 3, setting its wipers onto the calling trunk. The operation of the circuits and apparatus shown in Fig. 12 will now be described in detail.

55 It will be assumed that a subscriber connected to the first board desires a connection with a subscriber connected to the second board.

The calling subscriber establishes a connection with an idle final selector, as 400', in the manner hereinbefore described and the impulse relay 303² in this selector will then be energized. The calling subscriber then sends two series of dialling impulses 60 into the final selector, whereby its tens and

units designating switches are set and its wipers 353², 354², 355², 500, 356², 357² are guided onto the first trunk 505, 506 of the set of trunks leading to the desired boards. There may, of course, be two or more different boards accessible through the final selectors 400'. When the trunk 505, 506 is reached the relay 377² is energized and the test circuit through the test relay 395² is closed. All the operations up to this point 70 are similar to those hereinbefore described so that it is not deemed necessary to repeat this description here. If the first trunk line 506, 505 is free the test relay 395² will be energized and it will open the circuit of the operating magnet 374³ at 501, but if this trunk is engaged the relay 395² will not be energized and the magnet 374² will receive current impulses that flow from the positive pole through the interrupter 375², 374², 501, 80 wiper 500, bank contact 502 to the positive pole. The movement of the wipers will continue either until a free trunk is reached or until the wipers land on the last trunk of the group, when the wiper 500 will touch a 90 dead contact 504 so that impulses will cease flowing through 500, 501, magnet 374², 375² to the positive pole of the battery and the wipers will stop. The calling subscriber will then receive a busy signal in the ordinary way.

It will now be assumed that the first trunk 505, 506 is free. The test relay 395² will then be energized, as soon as the wipers of the connector reach this trunk, by a current 100 which flows from the negative pole through 393², 395², 355², test wire 513, cut-off relay (not shown) associated with the normals 511, 512 at the line finders (not shown) of the first board to the positive pole. The 105 said cut-off relay and line finders are arranged like the relay 109³ at the second board 600 and like the finder 100 of Fig. 3. The test relay 395² immediately renders the trunk 505, 506, busy at the first board by 110 short-circuiting a part of its winding and thus reducing the potential on the test wire 513, and at the same time closes the circuit of the ringing relay 347² and thus sends alternating current through the line relay 527 115 at the second board, this alternating current flowing from the ringing current generator 346², through 349², 401², 353², 505, 520, condensers 551, 527, 524, 523 and all the similar contacts of the relays of the other trunks 120 and subscribers' lines of the same group, condenser 552, battery, earth, 518, 506, 354², 400³, 345², ringing current generator 346². The line relay 527 responds and closes its contacts 526 and 529 so as to energize the 125 line finder starting relay 103³ and the auxiliary line relay 530, which latter receives current through the resistance 528 and attracts its easily moved armature so as to close the contact 525 and open contact 523. The 130

opening of contact 523 prevents a second call, that may arrive immediately afterwards, from affecting the line finder starting relay 103³, because the alternating current path through another relay 527, or the continuous current path through a line relay 102³ of any subscriber's line as 110³, 111³, will thus be interrupted at 523.

The closure of the contact 525 results in 10 a circuit for the relay 530 being immediately closed over the trunk line as follows: negative pole, 525, 520, 503, 353³, 401², 550, 15 left hand winding of the slow-acting relay 342² to earth. Immediately after the line 20 relay 527 and the line finder starting relay 103³ are energized a return impulse is sent back from the started finder through the wire 126³ in the manner hereinbefore explained and through the right hand winding 25 of the relay 530, and this relay then attracts its heavy armature so as to open its contacts 521, 524, 532 and close its contacts 522, 531, 533. The started line finder is stopped in the manner hereinbefore described as soon 30 as its wipers reach the bank contacts of the calling trunk, a current then flowing through the test or stopping relay (not shown) of the finder and through the test wiper 149³, contact 522, cut-off relay 517 to earth.

35 The trunk 505, 506 is then extended through the finder at the second board to the numerical switch (group selector or final selector) thereat and the calling subscriber then sets the selectors at the second board 40 by sending in further dialling impulses which are transmitted by the contact 550 into the numerical switches of the second board. The calling subscriber of the first board can thus select any line at the second board just as this can be done by any subscriber such as 101³ directly connected to the second board.

Any subscriber directly connected to the second board can also select the normals 514, 45 515, 516 through final selectors of the second board and can obtain connection with the trunk 505, 506 to the first board, this trunk being then extended to the selectors of the first board in the same way as this is done 50 at the second board when it is connected to from the first board. It is thus seen that two-way inter-group or inter-board trunking is accomplished in a novel and simple manner. If only one inter-board trunk line 55 instead of a plurality is provided the extra wiper 500 and its associated row of bank contacts can be omitted in the final selectors 400' and ordinary final selectors may be used.

60 It is to be noted that immediately an inter-board trunk as 505, 506 is connected to at the calling end or first board it is also rendered engaged at the second board by the energization of relay 530 which opens the contact 521 and makes the trunk appear en-

gaged at the final selector of the second board.

Instead of a finder with three magnets as shown in Figs. 1 and 2 a quick acting finder having only two magnets and wipers attached to the shaft instead of to a sleeve on the shaft may be employed. In this modification a sleeve or clutch member adapted to slide axially on the shaft may normally couple the latter with a ratchet wheel that is normally prevented from rotating by a detent. The sleeve clutch member may be moved axially by the one magnet (starting magnet) of the switch so as to uncouple the shaft from the ratchet wheel and a spring will then whirl the shaft of the wipers round at a high speed which may be governed by a speed regulator. When the group hunting wiper reaches the long contact that designates the group in which the contact set of the calling line or trunk is located the starting magnet is deenergized, allowing the sleeve clutch member to move back into engagement with the ratchet wheel. The ratchet wheel together with the clutch member and the shaft are now stepped round by a stepping magnet until the wipers reach the calling line. At the end of a connection the shaft whirling spring is rewound by the stepping magnet stepping the ratchet round until the spring is fully retensioned.

I claim:

1. In a telephone exchange system, a plurality of lines divided into groups, a line finder having a bank contact set allotted to each line and a long and short bank contact allotted to each group of lines, a power member continuously tending to operate said finder, means normally holding said finder against movement, means for operating said finder by said power member at a high rate of speed to select the group to which the desired line or calling line belongs, a stopping magnet for said finder, a circuit for said stopping magnet including a long bank contact, a magnet for operating said finder at a relatively low rate of speed, and a circuit including a short bank contact for controlling said last-mentioned magnet.

2. In a telephone exchange system, a plurality of lines divided into groups, a line finder having a bank contact set allotted to each line and two special contacts allotted to each group of lines, high-speed operating means for said finder, a magnet for arresting the high-speed operation of said finder, a circuit for said magnet including one of said special contacts, a magnet for operating the finder at a relatively low rate of speed, and a circuit for said magnet including the other special contact.

3. In a telephone exchange system, a plurality of lines divided into groups, a line finder having a set of bank contacts allotted to each line and two special bank contacts,

- allotted to each group of lines, a power member continuously tending to operate said finder, means normally holding the finder against operation, releasing means for said 5 finder to operate it by said power member at a high rate of speed to select the group to which the desired line or calling line belongs, a stopping magnet for said finder, a circuit for said stopping magnet including 10 one of said special bank contacts, a magnet for operating said finder at a relatively low rate of speed, and a circuit for said last mentioned magnet including the other special bank contact.
- 15 4. In a telephone exchange system, a plurality of finders having bank contacts and cooperating wipers, telephone lines connected to said bank contacts, a finder-starting relay common to a group of lines, a 20 two-step line relay for each line having contacts actuated upon partial magnetization of said relay and contacts actuated upon complete magnetization of said relay, a circuit for partially magnetizing said line relay 25 in response to the initiation of a call on the line associated therewith, said circuit including said finder-starting relay, and a circuit including the bank contacts and wipers of said finder for completely magnetizing 30 said line relay.
5. In a telephone exchange system, a plurality of lines, switching devices for establishing connections with said lines, a two-step relay associated with each line, said 35 relay having contacts actuated upon partial magnetization of the relay and contacts actuated upon complete magnetization of said relay, means common to a group of lines for initiating the operation of a switching device, a circuit closed thereupon for partially magnetizing one of said relays, and a circuit for completely magnetizing said relay controlled by contacts of said switching device.
- 45 6. In a telephone exchange system, a plurality of lines divided into groups, a two-step double-wound relay for each line having contacts operated upon partial and contacts operated upon complete magnetization 50 thereof, a group relay for each group of lines, a line-extending switch controlled by a group relay, a circuit extending through a group relay and one of the windings of a line relay for partially magnetizing the latter, and a circuit for completely magnetizing said line relay jointly controlled by a group relay and said line-extending switch.
- 55 7. In a telephone exchange system, a plurality of lines divided into groups, a marginal line relay for each line, a group relay having a high and a low resistance winding for each group of lines, line-extending switches controlled by said group relays, a circuit closed upon the initiation of a call 60 on any one of said lines including both windings of said group relay and the line relay of the calling line, and a shunt around the high resistance winding of the group relay controlled in contacts thereof.
- 70 8. In a telephone exchange system, a plurality of lines divided into groups, a marginal line relay having two windings for each line, a group relay having a high and a low resistance winding for each group of lines, line-extending switches controlled by said group relays, a circuit closed upon the initiation of a call and including one of the windings of the line relay and both windings of the group relay, a shunt path closed 75 around the high resistance winding of the group relay upon the energization thereof, and a circuit for the other winding of the line relay controlled by the line-extending switch.
- 80 9. In a telephone exchange system, a plurality of groups of lines, a plurality of line-extending switches, a line relay for each line, a group relay for each group of lines for controlling the operation of said 85 switches, an extended starter wire circuit for each group relay controlled in contacts of the line relays, and a low resistance shunt path closed around said group relay upon the energization thereof.
- 90 10. In a telephone exchange system, a plurality of groups of lines, a plurality of line-extending switches, a line relay for each line, a group relay for each group of lines for controlling the operation of said 95 switches, an extended starter wire circuit for each group relay controlled in contacts of the line relays, and a low resistance shunt path closed around a portion of the winding of a group relay upon the energization thereof.
- 100 11. In a telephone exchange system, a plurality of groups of lines, a plurality of line-extending switches, a line relay for each line, a group relay having a high and a low resistance winding for controlling the operation of said switches, an extended starter wire circuit for said group relay controlled in contacts of the line relays, and a shunt path closed around the high resistance 105 winding of a group relay upon the energization thereof.
- 110 12. In a telephone exchange system, a plurality of lines divided into groups, means including a line finder switch for extending a calling line, group selecting means in said line finder for operating it to select the group to which the calling line belongs, line-selecting means in the line finder for operating it to select the particular line calling, a line relay associated with each line, a group relay having relatively high and low resistance windings common to a group of lines, a plurality of contacts for each one of said relays, an extended starter wire cir-
- 115 120 125 130

cuit for said group relay including in series two back contacts of each line relay, a branch for said circuit completed upon the initiation of a call through the line relay associated with the line calling, an alternate path established thereupon through the relatively low resistance winding of the group relay and a front contact of the line relay of the calling line, a circuit including a group designating contact of the line finder and one of the contacts of the group relay, a magnet for operating the group selecting means of the line finder, a circuit for said magnet including another contact of said group relay, an energizing circuit for said line relay controlled by said magnet, an electromagnet for controlling the line selecting means of the finder, and a circuit for said electromagnet including another contact of said group relay.

13. In a telephone exchange system, a plurality of lines, means including a line finder for extending a calling line, a common relay for said lines for controlling the starting of said line finder, a high and a low resistance winding for said relay, a marginal line relay for each line, light armatures for said line relay adapted to be moved upon the partial magnetization of the relay, heavy armatures for said line relay adapted to be moved upon the complete magnetization thereof, a circuit including said line relay and windings of said common relay closed upon the initiation of a call for energizing said common relay and partially magnetizing the line relay of the calling line, said circuit including also back contacts controlled by the light armatures of said line relays in series, branch paths around said back contacts controlled in front contacts and heavy armatures of said line relays, means operative upon the energization of said common relay for closing a shunt path around its high resistance winding, and a circuit for completely magnetizing the line relay of the calling line established upon the starting of said line finder.

14. In a telephone system, finder switches, a group of lines connected to said switches, a relay having a single winding common to said group, a circuit including said winding for actuating said relay to start a finder switch upon the initiation of a call on one of said lines, and means also controlled by said relay for immediately thereafter starting a second finder switch upon the initiation of a call on another line while said first mentioned finder switch is still hunting for the calling line.

15. In a telephone system, finder switches, a group of lines connected to the finder switches, starting means including a non-differential relay controlled by a calling line for starting a finder switch, trunks, means

for preventing the said starting means from starting another finder until after a started finder has connected a trunk to the said calling line, and starting means including said relay controlled by a second calling line for starting a second finder switch while the first started finder is hunting for a calling line.

16. In a telephone system, finder switches, lines connected to the finder switches, calling means associated with the said lines, starting means normally associated with the lines and including a non-differential relay for sending a starting impulse to a finder when a line calls, means for dissociating all the lines from the starting means when a finder is started, and means for reconnecting the starting means to all the lines except the last calling line when the started finder has left its normal position.

17. In a telephone system, finder switches, lines connected to the finder switches, calling means associated with the said lines, a starting circuit for sending a starting current to a said finder when a line calls a non-differential relay associated with the calling line and adapted to dissociate the calling line from the starting circuit, a circuit for actuating the said relay when a finder is started, means for extending the starting circuit to another finder, and means for sending a starting current to the said other finder the moment the said relay is actuated.

18. In a telephone system, finder switches, lines, non-differential relays associated with said lines, means for sending an impulse from a calling line to a finder switch, means for sending an impulse from said last mentioned finder switch to the relay associated with the calling line, finder starting means responsive to the first mentioned impulse, and means responsive to the second mentioned impulse to disassociate the line from said impulse sending means.

19. In a telephone system, finder switches, lines, multiple-armature non-differential relays associated with said lines and means for sending an impulse from a line to a finder switch and from this finder switch to the relay associated with the said line when the line calls, whereby a finder is started and the line is dissociated from the said impulse sending means.

20. In a telephone system, groups of connectors, a group of line-extending switches associated with each group of connectors, a group of telephone lines connected to each group of connectors, and trunks leading from each group of connectors to every group of line-extending switches except its own group of line-extending switches.

21. In a telephone system, subscribers' lines, group selectors, wanted line connectors, primary trunks associated with the group selectors, secondary trunks associated

with the wanted line connectors, quick-acting line finders connected to the primary trunks adapted to hunt for calling subscribers' lines, intermediate trunks, quick-acting intermediate trunk finders connected to the secondary trunks and adapted to hunt for intermediate trunks, and means for extending a call from a subscriber's line through a line finder, group selector and intermediate trunk finder to a wanted-line connector, the said quick-acting finders being equipped with bank contacts, wipers and means for driving the wipers in a continuous high speed movement into any group of bank contacts that has a contact set connected to a calling line or trunk.

22. In a telephone system, telephone instruments, groups of primary trunks, groups of secondary trunks, groups of two-wire intermediate trunks, primary finders for connecting the telephone instruments to the primary trunks, group selectors associated with the primary trunks and adapted to select groups of intermediate trunks, intermediate trunk finders for finding intermediate trunks, and connectors for connecting intermediate trunks to wanted telephone instruments.

23. In a telephone system, telephone instruments, groups of primary trunks, groups of secondary trunks, groups of two-wire intermediate trunks, a finder-affecting relay associated with each intermediate trunk, primary finders for connecting the telephone instruments to the primary trunks, group selectors associated with the primary trunks and adapted to select groups of intermediate trunks, intermediate trunk finders for finding intermediate trunks, and connectors for connecting intermediate trunks to wanted telephone instruments.

24. In a telephone system, telephone instruments, groups of primary trunks, groups of secondary trunks, groups of two-wire intermediate trunks, a finder-affecting relay associated with each intermediate trunk and adapted to be energized over one wire of its trunk only, primary finders for connecting the telephone instruments to the primary trunks, group selectors associated with the primary trunks and adapted to select groups of intermediate trunks, intermediate trunk finders for finding intermediate trunks, and connectors for connecting intermediate trunks to wanted telephone instruments.

25. In a telephone system, connectors, group selectors, two-wire trunks adapted to be selected by the group selectors and trunk finders for connecting a connector to a two-wire trunk that has been selected by a group selector.

26. In a telephone system, connectors, non-hunting group selectors, two-wire trunks adapted to be selected by the group selectors and trunk finders for connecting a con-

necter to a two-wire trunk that has been selected by a group selector.

27. In a telephone system, connectors, group selectors, two-wire trunks adapted to be selected by the group selectors and trunk finders for connecting a connector to a two-wire trunk that has been selected by a group selector.

28. In a telephone system, calling lines, primary trunks, non-numerical switches for extending calling lines to the primary trunks, secondary trunks, intermediate two-wire trunks, group selectors for extending calls from the primary trunks to the intermediate trunks, and finders for extending the two-wire trunks to the secondary trunks.

29. In a telephone system, calling lines, primary trunks, non-numerical switches for extending calling lines to the primary trunks, secondary trunks, intermediate two-wire trunks, group selectors for extending calls from the primary trunks to the intermediate trunks, a trunk-marking relay associated with each two-wire trunk and adapted to mark it when it has been selected, and finders for extending marked two-wire trunks to the secondary trunks.

30. In a telephone system, calling lines, primary trunks, non-numerical switches for extending calling lines to the primary trunks, secondary trunks, intermediate two-wire trunks, group selectors for extending calls from the primary trunks to the intermediate trunks, a trunk marking relay connected to only one wire of a two-wire trunk and adapted to mark it when it has been selected, and finders for extending marked two-wire trunks to the secondary trunks.

31. In a telephone system, calling lines, primary trunks, non-numerical switches for extending calling lines to the primary trunks, secondary trunks, intermediate two-wire trunks, group selectors for extending calls from the primary trunks to the intermediate trunks, a trunk marking relay connected to only one wire of a two-wire trunk and adapted to mark it when it has been selected, finders for extending marked two-wire trunks to the secondary trunks, and a cut-off relay for disconnecting a marking relay from its trunk.

32. In a telephone system, groups of numerical switches, finders connected to the numerical switches, two-wire trunks connected to the multiples of the finders, non-hunting group selectors for selecting said trunks, means controlled through one wire of a said trunk for indicating the trunk as a calling trunk and starting a finder, and means for setting a started finder onto a calling trunk.

33. In a telephone system, groups of numerical switches, finders connected to the numerical switches, two-wire trunks connected to the multiples of the finders, non-hunting group selectors for selecting said

- trunks, repeaters associated with the group 50
selectors, means controlled through one wire
of a said trunk for indicating the trunk as
a calling trunk and starting a finder, means
for setting a started finder onto a calling
trunk, and means for sending a current over
the other wire of the said trunk to a repeater
after the finder has found the indicated
trunk.
34. In a telephone system, lines, a group of
wanted line connectors for establishing
connections with wanted lines, finders associated
with the wanted line connectors, two-wire trunks connected to the multiples of the
finders, non-hunting group selectors for
selecting said trunks, means controlled
through one wire of a said trunk for indicating
the trunk as a calling trunk and starting
a finder, means for setting a started
finder onto a calling trunk, a circuit changer
at each group selector, and means for
sending current over the other wire of the
said trunk to a circuit changer when a
wanted line connector connects to a wanted
line.
35. In a telephone system, telephone lines;
wanted line connectors each consisting of a
main switch with contact banks and cooperating
wipers, auxiliary switches with contact
banks and cooperating wipers for marking
contact groups and individual contacts of
the main switch; and quick-acting finders
for extending calls to the wanted line con-
nectors, the quick-acting finders having
wipers, means for moving the wipers in a
continuous high speed movement into a
group of contacts in which there is a call-
ing line, and means for then moving the
wipers at a lower speed onto the calling line
itself.
36. In a telephone system, finders having
contacts, subscribers' lines connected to cer-
tain contacts of the finders, and trunks con-
nected to other contacts of the said finders.
37. In a telephone system, wanted line con-
nectors, finders having contacts, subscribers' lines connected to certain contacts of the
finders, and trunks leading from the
wanted lines connectors to other contacts of
the finders.
38. In a telephone system, finders having
contacts, conversational circuits connected
to the contacts of the finders, continuous
current calling relays associated with some
of the said conversational circuits, and alter-
nating current calling relays associated with
another of the said conversational circuits.
39. In a telephone system, finders hav-
ing contacts, subscribers' lines connected to
certain contacts of the finders, and two-way
trunks connected to other contacts of the
finders.
40. In a telephone system, finders having
contacts, a group of wanted line connectors,
a trunk leading from the group of wanted
line connectors to the contacts of the
finders, line connectors to the contacts of the
finders, and subscribers' lines connected to
the contacts of the finders.
41. In a telephone system, finders having
contacts, a group of wanted line connectors,
trunks leading from the wanted line connectors
to the contacts of the finders, and sub-
scribers' lines connected to the contacts of
the finders.
42. In a telephone system, wanted line
connectors each comprising a main switch
and an auxiliary steering switch, finders
having bank contacts, subscribers' lines con-
nected to the bank contacts of the finders,
and a trunk leading from an auxiliary
switch of a connector to the banks of the
finders.
43. In a telephone system, wanted line
connectors each comprising a main switch
and an auxiliary steering switch, finders
having bank contacts, subscribers' lines con-
nected to the bank contacts of the finders,
and trunks leading from the auxiliary
switches of the connectors to the banks of
the finders.
44. In a telephone system, finders having
bank contacts, subscribers' lines connected to
certain bank contacts of the finders, trunks
connected to other bank contacts of the said
finders, and a finder controlling relay as-
sociated with each line and trunk adapted to
be actuated over only one wire of the line
or trunk.
45. In a telephone system, wanted line
connectors, finders having bank contacts,
subscribers' lines connected to certain bank
contacts of the finders, trunks leading from
the wanted line connectors to other bank
contacts of the finders, and a finder-control-
ling relay associated with each line and
trunk adapted to be actuated over only one
wire of the line or trunk.
46. In a telephone system, finders having
contacts, subscribers' lines connected to cer-
tain contacts of the finders, two-way trunks
connected to other contacts of the finders,
and a finder-controlling relay associated
with each line and trunk adapted to be actuated
over only one wire of the line or trunk.
47. In a telephone system, finders having
bank contacts, a group of wanted line con-
nectors, a trunk leading from the group of
wanted line connectors to the banks of the
said finders, subscribers' lines connected to
the banks of the said finders, and a finder-
affecting relay associated with each line and
trunk adapted to be actuated over only one
wire of the line or trunk.
48. In a telephone system, finders having
bank contacts, a group of wanted line con-
nectors, trunks leading from the wanted line
connectors to the banks of the finders, sub-
scribers' lines connected to the banks of the
said finders, and a finder-affecting relay as-
sociated with each line and trunk adapted

to be actuated over only one wire of the line or trunk.

49. In a telephone system, wanted line connectors each comprising a main switch and an auxiliary steering switch, finders having bank contacts, subscribers' lines connected to the bank contacts of the finders, a trunk leading from an auxiliary switch of a connector to the banks of the finders, and a finder-affecting relay associated with each line and trunk adapted to be actuated over only one wire of the line or trunk.

50. In a telephone system, wanted line

connectors each comprising a main switch and an auxiliary steering switch, finders having bank contacts, subscribers' lines connected to the bank contacts of the finders, trunks leading from the auxiliary switches of the connectors to the banks of the finders, and a finder-affecting relay associated with each line and trunk adapted to be actuated over only one wire of the line or trunk.

In testimony whereof I affix my signature.

FRITZ ALDENDORFF.
